International Search Report and Written Opinion dated Mar. 11, 2014
of International Application No. PCT/JP2014/051998.*Primary Examiner* — Cynthia Ramirez*Assistant Examiner* — Gino Colan(74) *Attorney, Agent, or Firm* — Maschoff Brennan(57) **CLAIM**

The ornamental design for a stepladder, as shown and described.

DESCRIPTION

FIG. 1 is a front perspective view of a stepladder showing our new design;

FIG. 2 is a bottom perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is an exploded perspective view thereof;

FIG. 10 is a rear view thereof in a collapsed position; and,
FIG. 11 is a front view thereof, in which one of the legs is folded.

The features shown in broken lines in the drawings depict environmental subject matter only and form no part of the claimed design.
